UNITED STATES PATENT OFFICE.

MARK GELDER, OF CHICAGO, ILLINOIS.

COMBINED STOOL AND RACKET-PRESS.

1,151,935.

Specification of Letters Patent. Patented Aug. 31, 1915.

Application filed May 14, 1915. Serial No. 28,002.

To all whom it may concern:

Be it known that I, MARK GELDER, a citizen of the United States, residing at Chicago, in the county of Cook and State of Illinois, have invented certain new and useful Improvements in Combined Stools and Racket-Presses, of which the following is a specification.

My invention relates to a device that may be used as a case or press for a tennis racket whereby the frame of the racket will be held in proper position to prevent its warping and, upon removal of the racket from the press, the press may be converted into a stool or seat.

The principal object of my invention is to produce a structure having the dual functions of a combined racket press and stool which will be light and compact and at the same time efficiently accomplish its intended purposes.

In the accompanying drawing: Figure 1 is a side elevational view of my device with the press in closed position and the legs of the stool in open position. Fig. 2 is a side elevational view of Fig. 1. Fig. 3 is a side elevational view of my device with the legs in closed position and the press partially open. Fig. 4 is a side elevational view of my device in operative position as a stool. Fig. 5 is a section on the line 5—5 of Fig. 2. Fig. 6 is an enlarged sectional view on the line 6—6 of Fig. 1. Fig. 7 is an enlarged sectional view on the line 7—7 of Fig. 1. Fig. 8 is a detailed view of a portion of the press frame, showing the manner of attaching the flexible seat thereto. Fig. 9 is a section on the line 9—9 of Fig. 8.

Referring now more particularly to the drawing, the main supporting element of the structure consists of a casting 10, preferably square in cross section, and provided with a pair of spaced lugs 11 on each side thereof. Each leg 12 has its upper end projecting between one of the pairs of lugs 11 and secured to said lugs by means of the hinge pins 13. The upper end of each leg is slightly cut away, as shown at 14, whereby the outward movement of the legs will be limited by the casting 10 and a substantial bearing surface provided.

The feet 15 are connected to the lower end of each leg. In order to prevent the legs from collapsing, when in open position, a pair of links 16 are pivotally connected to each adjacent pair of legs, at their outer

ends, by the pins 19, and each pair of links are connected together at their inner ends by the pins 20. One of the links 16 is formed with a flange 21 that is adapted to overlie the upper edge of the complementary link and thus limit relative movements of each pair of links in one direction.

The press and seat portion of the device comprises two main frame members 22, having lugs 23 at their lower ends through which lugs the hinge pins enter into suitable recesses formed in the ears 25 upon the casting 10. The lugs 23 are provided with stops 26 which bear against the casting 10 and thus limit the outward movement of the frames 22. Each frame 22 has a portion 27 of its face disposed at an angle to its other face portion, for a purpose hereinafter to be described.

Supplementary frame members 28 are pivotally connected to the outer ends of the main frame members and in the construction herein shown this pivotal connection is accomplished by forming recesses 29 upon opposite sides of the main frame member and lugs 30 are formed upon the inner ends of the supplementary frame members, adapted to enter said recesses and the two parts of the frame members being joined by the hinge pins 31.

Upon each main frame member and along its outer edge, are preferably three hooks 32. Two of these hooks upon each main frame member serve as stop pins to limit the movement of the supplementary frame members relative to the main frame members, in one direction, and also serve as the attaching medium for the seat, which will now be described.

The seat comprises a flexible piece of material 33, such as canvas, having a reinforcing strip of material 34, such as wire, at each end thereof. Spaced openings 35 are formed in the seat 33 adjacent the reinforcing strips; said openings being so spaced as to register with the hooks 32.

When the main frame members are partially separated the seat member is connected to the opposite main frame members by inserting the hooks 32 within the openings 35, whereupon the main frame members are moved downwardly upon their hinges until the seat member 33 is substantially flat.

In order to make the structure more rigid, when used as a seat, two bails 36 are employed; the bails being secured to oppo-

sitely disposed legs and pivotally connected thereto at their lower ends while the upper end of each bail is provided with a hook 37 adapted to enter a suitable aperture in the 5 lugs 38 formed upon each main frame member and substantially centrally thereof.

The structure as illustrated in Fig. 4 is in complete operative position as a stool and when used as such the supplementary frame 10 members perform no function whatsoever.

As a racket press the structure is best illustrated in Figs. 1, 2 and 3. The racket 39 is inserted between the main frames with its handle portion extending through the main 15 casting 10. The main frames 22 are then moved toward the racket frame until the surfaces 27 of the main frames bear flat against opposite sides of the racket frame. The supplementary frame members are then 20 brought in contact with the opposite sides of the racket frame whereupon clamps are employed for holding the frames together. The number of clamps used may be varied and in the accompanying drawings, I have 25 shown two clamps 40 upon the supplementary frame near its lower hinged edge and upon opposite sides thereof; clamps 41 at the top of the supplementary frame, and upon opposite sides of the center, and a center clamp 42. Each clamp herein referred to consists of a block 43 that is provided with a central threaded aperture 44. One end of each block is confined between a pair of lugs 45 secured to one of the supplementary 30 frame members and the block 43 is held between the lugs 45 by the hinge pin 46. A hook 47 has a threaded end adapted to engage the threads in the recess 44. Oppositely disposed upon the other supplementary 35 frame member is a cam latch 48 that is mounted upon a hinge pin 49 the ends of which are confined within lugs 50. The cam latch 48 is provided with a recess 51 near the hinge pin and into which recess the hook 45 end 52 of the hook 47 is adapted to project. The hook 47 may be adjusted relative to the block 43 whereby the latch will draw the 40 two parts of the supplementary frame member against opposite sides of the racket 45 frame.

It is, of course, understood that there are numerous minor details which may be changed without departing from the spirit of the invention and

55 Having shown and described the preferred form of construction, I claim:

1. A combined stool and racket press comprising, a supporting member, a pair of frame members movably connected thereto, 60 a plurality of legs movably connected to said supporting member, means for pre-

venting the separation of said frame members, and a seat member adapted to be connected to said frame members.

2. A combined stool and racket press comprising, a supporting member provided with a central opening, a pair of frame members pivotally connected thereto, a plurality of legs pivotally connected to said supporting member, means for holding said legs in 65 spaced relation, means for holding said frame members in fixed relation when in closed position and a seat member adapted to be connected to said frame members.

3. A combined stool and racket press comprising, a supporting member provided with a central opening, a pair of main frame members pivotally connected thereto, a pair of supplementary frame members hinged to 70 said main frame members, a plurality of legs pivotally connected to said supporting member and a seat member adapted to be connected to said main frame members.

4. A combined stool and racket press comprising, a supporting member, a pair of two 75 part frame members pivotally connected thereto, a plurality of legs pivotally connected to said supporting member, a seat member adapted to be connected at its ends to said frame members and means for drawing 80 said frame members toward each other.

5. A combined stool and racket press comprising, a supporting member, a pair of frame members pivotally connected thereto, means for limiting the movement of said 95 frame members relative to said supporting member, a plurality of legs pivotally connected to said supporting member, means for holding said legs in spaced relation, a seat member adapted to be connected to said 100 frame members and means for holding said frame members in an open position.

6. A combined stool and racket press comprising, in combination, a supporting member, a pair of frame members movably connected thereto, a plurality of legs movably connected to said supporting member and means for drawing the frame members 105 against the frame of said racket.

7. A combined stool and racket press comprising, a supporting member, a pair of oval shaped frame members secured to said supporting member, legs movably secured to said supporting member, a seat member adapted to be secured between said frame 115 members and means carried by said frame members for drawing said frame members toward each other.

MARK GELDER.
